CLAIM

The ornamental design for a tool waistband, as shown and described.

DESCRIPTION

FIG. 1 is a front, right and bottom perspective view of a tool waistband, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an exploded view thereof; and,

FIG. 10 is a front, right and top perspective view of the tool waistband in a usable state.

The broken lines shown in the drawings are included for the purpose of illustrating portions of the tool waistband that form no part of the claimed design. The broken lines shown in FIG. 9 are included for the purpose of illustrating environmental structure and forms no part of the claimed design.
